CLAIM

The ornamental design for a switch, as shown and described.

DESCRIPTION

FIG. 1 is a front, top, right side perspective view of a first embodiment of a switch showing my new design;

FIG. 2 is a rear, bottom, left side perspective view thereof; FIG. 3 is a front view thereof, the rear view being identical to the front view;

FIG. 4 is a left side view thereof, the right side view being identical to the left side view;

FIG. 5 is a top plan view thereof;

FIG. 6 is a bottom plan view thereof;

FIG. 7 is a front, top, right side perspective view of a second embodiment of a switch showing our new design;

FIG. 8 is a rear, bottom, left side perspective view thereof; FIG. 9 is a front view thereof, the rear view being identical to the front view;

FIG. 10 is a left side view thereof, the right side view being identical to the left side view;

FIG. 11 is a top plan view thereof; and,

FIG. 12 is a bottom plan view thereof.

In the drawings, the broken lines depict portions of the switch that form no part of the claimed design.

1 Claim, 12 Drawing Sheets
